(57) **CLAIM**

The ornamental design for a lawn tractor grill and air intake cowl assembly, as shown and described.

DESCRIPTION

FIG. 1 is a front perspective view of a grill and air intake cowl for a lawn tractor showing our new design in use condition;

FIG. 2 is an enlarged front perspective view thereof;

FIG. 3 is a front elevation view thereof;

FIG. 4 is a right side elevation view thereof, the left side elevation view is a mirror image thereof; and,

FIG. 5 is a top plan view thereof.

The bottom view forms no part of the claimed design.

The phantom lines shown in the drawing Figures are meant to illustrate environment only and form no part of the claimed design.

1 Claim, 5 Drawing Sheets
